VALVE CAP FOR TIRE VALVE INSERTS, INNER TUBES AND THE LIKE

George P. McCord, Indianapolis, Ind., assignor to United States Rubber Company, New York, N.Y., a corporation of New Jersey

Filed June 5, 1963, Ser. No. 75,228

Term of patent 14 years

(Cl. D90—20)

FIG. 1—1

FIG. 2—2

FIG. 3—3

FIG. 1 is a top plan view of a valve cap for tire valve inserts, inner tubes and the like showing my new design.

FIG. 2 is a side elevation view thereof.

FIG. 3 is a bottom plan view thereof.

I claim:

The ornamental design for a valve cap for tire valve inserts, inner tubes and the like, as shown and described.
